A. E. OSTRANDER AND H. H. WILLIAMS.

JOURNAL BOX.

APPLICATION FILED MAR. 23, 1921.

1,415,108.

Patented May 9, 1922.

INVENTORS:

Allen E. Ostrander
and Herbert H. Williams

BY *J. H. Gibbs*

ATTORNEY.

UNITED STATES PATENT OFFICE.

ALLEN E. OSTRANDER, OF RIDGEWOOD, NEW JERSEY, AND HERBERT H. WILLIAMS, OF BROOKLYN, NEW YORK, ASSIGNORS OF ONE-HALF TO AMERICAN CAR AND FOUNDRY COMPANY, OF NEW YORK, N. Y., A CORPORATION OF NEW JERSEY, AND ONE-HALF TO METROPOLITAN ENGINEERING COMPANY, OF BROOKLYN, NEW YORK, A CORPORATION OF NEW YORK.

JOURNAL BOX.

1,415,108.

Specification of Letters Patent. Patented May 9, 1922.

Application filed March 23, 1921. Serial No. 454,762.

To all whom it may concern:

Be it known that we, ALLEN E. OSTRANDER and HERBERT H. WILLIAMS, residing at Ridgewood, county of Bergen, and State of New Jersey, and Brooklyn, county of Kings, and State of New York, respectively, and being citizens of the United States, have invented certain new and useful Improvements in a Journal Box, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is a central vertical section of our improved journal box;

Figure 2 is in part a top plan view and in part a horizontal section of our improved journal box;

Figure 3 is in part an elevation of the dust guard pocket end of the box and in part a section on the line 3—3 of Fig. 2; and

Figure 4 is a section of one-half of the box taken on the line 4—4 of Fig. 2.

It is the object of our invention to provide an improved pressed metal journal box that shall be of great strength and durability and can be manufactured at comparatively small cost.

In the drawing, 1 and 2 designate two pressings, each of which forms one-half of the box. The two halves have the same contour except that they are intended to form opposite halves of the box. Each half comprises a side 3 and half of the top 4, the bottom 5 and the rear wall 6 of the box. The rear wall 6 is separated from the top 4 so as to leave an opening 7 in which the dust guard container 8 is inserted. The sides 3 are corrugated, as at 9, the corrugation 50 widening as it approaches the bottom 5 of the box and extending completely across the bottom. At the bottom the corrugation 9

forms a recess adapted to receive the lower yoke 10 which is provided with openings to receive the journal box bolts. The yoke 10 is also recessed to receive the box so that stresses are transmitted from one to the other without danger of rupturing the welds 11 that secure the yoke 10 to the box.

A reenforcing member 12, of cast steel or a drop forging, has formed integral therewith projections 13 provided with openings adapted to receive the journal box bolts, the projections 14 recessed to receive the corrugations in the box sides and adapted to form stops for the journal brass, projections 15 forming stops for the journal box wedge and hinge lugs 16. The pressings 1 and 2 are provided with openings 17 through which extend the projections 13, part of the metal cut away to form the openings being bent outwardly to form shoulders 18 upon which the projections 13 rest. The top 4 is also cut away, as at 19, to form an opening to receive the hinge lugs 16.

The dust guard container 8 comprises a metal sheet flanged on all sides and shaped to fit the box. The dust guard is slipped into this receptacle and the whole forced into the opening 7.

In assembling the box, the projections 13 on the reenforcing member 12 are slipped into the openings 17, then the two pressings are brought together and welded along the center line 20 of the box, the reenforcing member 3 being in this way secured in position in the box. The yoke 10 is then secured to the box.

What we claim is:

1. A journal box comprising sections meeting in a vertical plane of the box and a reenforcing member secured in place by said sections. 90

2. A journal box comprising sections meeting in a vertical plane of the box and a reenforcing member secured in place by said sections and having projections extending through openings in said sections. 95

3. A journal box comprising a plurality of sections, a reenforcing member engaging said sections and held in position in said box upon securing said sections together. 100

4. A journal box comprising a plurality of sections and a reenforcing member having

projections extending through openings in said sections and held in position upon welding said sections together.

5. A journal box comprising a plurality of 5 sections and a reenforcing member secured in place by said sections and having projecting portions adapted to receive the journal box bolts.

6. A journal box comprising a plurality of 10 sections having corrugations therein and a reenforcing member secured in place by said

sections and having lugs adapted to fit said corrugations and serve as journal brass stops.

In witness whereof we have hereunto set 15 our hands in the presence of two witnesses.

ALLEN E. OSTRANDER.
HERBERT H. WILLIAMS.
